CLOTH BOARD

Edward F. King, Cranston, R. I.

Application June 20, 1933, Serial No. 676,659

7 Claims. (Cl. 206—50)

This invention relates to an improved cloth board of the type employed as a support for a web or roll of woven fabric to facilitate the handling and display of the same as well as to provide for the ready removal of a portion of the fabric.

One object of the invention is the provision of a cloth board of this character which is of light weight and rigid construction, and which is capable of being made and assembled more cheaply than the usual devices of this character now in use.

Another object of the invention is the provision of a device of this character so constructed and arranged as to provide a tensioned effect between the cover and frame which serves to hold the cover under tension and at the same time to retain the frame parts in a position of rigidity.

A further object of the invention is the provision in a device of this character of a cover means or strip of sheet material surrounding the frame and attached thereto only at points adjacent the frame ends, whereby that portion of the cover strip located intermediate the frame ends is maintained free from wrinkles or folds to form a uniformly even surface of the board.

Another object of the invention is the provision in a structure of this character of a frame comprising side rails of a resilient character having outwardly flaring edge portions adapted for engagement with the cover strip to impart reciprocal tension to the strip and frame.

Another object of the invention is the provision of novel connecting means between the side rails and spacing members, whereby the side rails are capable of slight movement towards and from each other to permit the rails to be drawn closely against the spacing members by the tension exerted thereon by the cover strip to increase the rigidity of the frame.

Other objects and advantages of the invention relate to various improved details of construction and arrangements of the parts as will be more fully set forth in the detailed description to follow.

Referring to the drawing:—

Fig. 1 is a perspective view of the improved cloth board, a portion of the cover strip being broken away to indicate more clearly the manner of securing the same to the frame.

Fig. 2 is a perspective view of the frame showing the parts in assembled relation and with the cover removed.

Fig. 3 is a transverse sectional view, taken substantially along the line 3—3 of Fig. 2, and illus-

trating the cross sectional shape of the opposed side rails.

Fig. 4 is a transverse sectional view, taken substantially along the line 4—4 of Fig. 2.

Fig. 5 is a detail sectional view showing the means connecting one of the side rails with one of the end spacing members, taken substantially along the line 5—5 of Fig. 2, and

Fig. 6 is a detail sectional view through one of the end spacing members, taken substantially along the line 6—6 of Fig. 2.

In that form of the invention illustrated herein the frame 1 comprises a pair of opposed side rails 2, which are preferably formed from thin metal or other suitable material such as is capable of being readily shaped to the desired form and which possesses a fair degree of resiliency.

Each of the side rails is shaped to provide a transversely curved portion 3 terminating in outwardly flaring edge portions 4 extending substantially throughout the entire length of each side rail. The flaring edge portions 4 may be so formed as to lie in planes substantially tangential to the curve of the rounded or curved portion 3 of each side rail and extend initially throughout substantially the entire length of the rail and upon opposite sides of the plane of the frame.

A plurality of spacing members may be interposed between the opposed side rails, which in the present instance comprise oppositely positioned end members 5 and an intermediate spacing member 6. The opposed end members 5 are of similar construction and each may be provided with opposite side walls 7 spaced from each other a distance substantially equal to the thickness of the completed cloth board, and a wall 8 which serves to form one end wall of the completed cloth board. The end spacing members 5 are also provided with rounded end portions 9 shaped to fit within and conform substantially with the curved portions 3 of the side rails.

The intermediate spacing member 6 is similarly provided with opposite side walls 11 adapted to be located substantially within the planes of the side walls 7 of the end members when the parts are assembled, a wall 12 connecting the opposed side walls 11, and rounded end portions 14 adapted to fit within and conform substantially with the curved portion 3 of the opposed side rails.

The end spacing members 5 may each be provided with a shallow recess or depression 16 formed in the outer face of the end wall 8, which may be shaped to provide substantially straight lateral shoulders 17 in such a manner that a

designating strip of paper or the like 18 may be inserted within the depression in such a manner that the opposite side edges of the strip 18 will frictionally engage the straight shoulders 17 whereby the strip 18 may be substantially retained within the depression 16 through engagement of its side edges with the lateral shoulders 17.

In practice it is regarded as preferable that the 10 opposed side rails be secured to the end spacing members 5 only by some form of securing means which will permit if desired a slight degree of play between the flaring portions 4 of the side rails and the adjacent surfaces of the end spacing members, and as illustrating one form of such attaching means which may be advantageously employed there is shown in Figs. 3 to 6 inclusive, cooperating lugs 20 and 21 formed by being struck out from the metal of the side rails 20 and end spacing members and arranged in substantially interfitting relation with each other, the planes of the lugs 20 and 21 being located at substantially right angles to the longitudinal extent of each side rail. In the present instance a 25 plurality of interfitting lugs 20 and 21 are provided between each side or flaring portion of each rail and the adjacent portion of each end spacing member, although the number of interfitting lugs provided may be increased or decreased 30 as found desirable or in order to permit greater or less freedom of movement between the flaring edge portions 4 of the side rails and the adjacent portions of the opposed end spacing members.

In the present instance the spacing members 35 5 and 6, like the opposed side rails 2, are shown as being formed from thin metal, and are drawn or otherwise shaped to give them the desired form approximating the cross sectional shape of the completed cloth board. It will be understood 40 however that the spacing members 5 and 6 may be formed from various other materials possessing the necessary rigidity and adapted to serve as supports for the side rails.

In making the frame 1 the several parts may 45 be assembled in substantially the form shown in Fig. 2 of the drawing, and the lugs 20 and 21 of the desired number and arrangement formed by subjecting the assembled parts to the operation of suitable automatic punches for striking out 50 the interfitting lugs.

Upon completion of the frame 1 a sheet 22 of 55 paper or other suitable fabric material is placed therearound in a direction transversely of the frame and has its free ends pasted or otherwise secured together to form a substantially continuous cover strip surrounding the frame and serving as a cover for the frame. In applying the cover strip 2 it is desirable that the strip be fixedly secured to the frame only at points adjacent to the frame ends, and for this reason the frame ends extending outwardly from the lines 60 24 are preferably treated with a suitable composition of material such as a bronze or aluminum lacquer or paint, or a varnish, or a combined lacquer and varnish to cause the paste or glue placed upon one side of the strip 22 to adhere 65 to the external surfaces of those portions of the frame located outwardly of the lines 24 as indicated in Fig. 2 of the drawing. In order that there may be no adhesion of the cover strip to 70 those portions of the frame located intermediate of the lines 24, those portions of the frame structure lying between the lines 24 may be oil treated or otherwise prepared to render the paste or glue carried by the cover strip ineffective to cause ad-

hesion between the cover strip and the intermediate portions of the frame. The adhering portion of the cover strip is indicated more particularly by the reference character 25 as shown in Fig. 1, while the non-adhering portion is indicated by 5 the reference character 26 in that figure.

The cover strip may be coated upon one side thereof with a suitable adhesive throughout its entire area and is preferably moistened before its application to the frame. The free end portions 10 of the cover strip are secured together by the adhesive as previously described. As the cover strip is applied it is drawn fairly closely about the opposed side rails, and as the cover strip dries, it contracts slightly, and draws against the flaring edge portions 4 of the side rails, which, in turn, tend to press it outwardly by reason of the resiliency inherent in the side rail members, thereby tensioning the cover strip more or less uniformly throughout the major portion of its 20 extent. This in turn reacts upon the opposed side rails to draw them towards each other. The reciprocal tensioning effect between the flaring edge portions 4 of the side rails and the cover strip 22 imparts a high degree of rigidity to the 25 frame and gives a smooth and tensioned effect to the cover strip throughout substantially its entire area.

The resulting cloth board is capable of being 30 readily constructed and provides a device of this character which is of extremely light weight, while possessing great firmness and rigidity.

What I claim is:—

1. In a cloth board, a frame comprising oppositely positioned rail members and spacing members 35 interposed between said rail members, and a continuous strip of sheet material extending about said frame, portions of said rail members resiliently engaging said strip to provide a tensioned support therefor and said sheet material 40 having portions of its opposed side edges secured to portions of the frame ends and having that part intermediate said frame ends bearing against but unattached to the intermediate portion of the frame.

2. In a cloth board, a frame comprising oppositely positioned rail members and spacing members interposed between said rail members, means 45 securing the end portions of said rail members to opposed spacing members to permit movement of portions of said rail members relative to said spacing members in a direction transversely of said frame for tensioningly supporting a strip of sheet material, and a strip of sheet material extending about said frame and having 50 its end portions interconnected, said sheet material having its opposed side edges only attached to portions of said frame adjacent to the opposite ends of said frame.

3. In a cloth board, a supporting frame comprising opposed rail members formed of thin resilient material and curved transversely throughout their lengths, spacing members interposed between said opposed rail members and provided with curved end portions fitting substantially 65 within the transversely curved portions of said rails, the transversely curved portions of said rail members terminating in outwardly flaring longitudinal edges initially extending outwardly of the planes defined by opposite sides of the 70 spacing members, and a continuous strip of sheet material extending about said rail members for tensioned engagement by the flaring edge portions thereof.

4. A cloth board comprising a supporting 75

frame having opposed tensioning rail members provided with resilient portions and a plurality of spacing members engaging said rail members, means for connecting the end portions of said rail members with portions of certain of said spacing members, and an end connected strip of sheet material passed about said rail members and enclosing a substantial portion of said frame, said strip of sheet material being attached directly to the frame only at the opposite side edges of the strip whereby the intermediate portions of said strip may be subjected to a substantially uniformly distributed tension from the resilient portions of said rails.

5. In a cloth board, a supporting frame comprising opposed rail members provided with curved portions having outwardly flaring resilient edge portions and spacing members interposed between said rail members, and a substantially continuous strip of sheet material surrounding said frame and overlying said rail members for tensioning engagement by the outwardly flaring portions of said rail members to tension said strip of sheet material substantially uniformly 15 throughout the major portion of its extent.

6. A cloth board frame comprising a plurality of spacing members provided with curved end portions and opposed side portions, opposed side rails each provided with a laterally curved central portion and flaring edge portions normally extending outwardly from the planes defined by the opposed side portions of said spacing members, and means for connecting portions of said side rails with portions of certain of said spacing members in such a manner as to permit slight 10 movement of the interengaged portions of said side rails and spacing members relative to each other.

7. A cloth board comprising a supporting frame provided with an end member having a 15 transversely curved longitudinal recess formed in the outer face thereof, and having substantially straight shoulders forming the opposite side edges of said recess for receiving a designating strip in 20 such a manner as to retain the strip in position within said recess through frictional engagement of the edges of said strip with the said lateral shoulders.

EDWARD F. KING. 25
